DESIGN FOR A HANDLE FOR A COOKING PAN OR SIMILAR ARTICLE

George A. Weinig, Dover, Ohio

Application July 23, 1936, Serial No. 63,996

Term of patent 14 years

To all whom it may concern:

Be it known that I, George A. Weinig, a citizen of the United States and a resident of Dover, county of Tuscarawas, and State of Ohio, have invented a new, original, and ornamental Design for a Handle for a Cooking Pan or Similar Article, of which the following is a specification, reference being had to the accompanied drawing, forming a part thereof.

In the drawing:

Fig. 1 is a side elevational view of the handle, showing my design.

Fig. 2 is a top plan view.

Fig. 3 is a sectional view taken substantially on the line 3—3 of Fig. 1.

I claim:

The ornamental design for a handle for a cooking pan or similar article, as shown.

G. A. WEINIG.
